UNITED STATES PATENT OFFICE.

AUGUSTUS H. HEISEY, OF IDLEWOOD, PENNSYLVANIA.

MACHINE FOR FINISHING ARTICLES OF GLASSWARE.

SPECIFICATION forming part of Letters Patent No. 663,023, dated December 4, 1900.

Application filed February 2, 1898. Serial No. 668,802. (No model.)

To all whom it may concern:

Be it known that I, AUGUSTUS H. HEISEY, a resident of Idlewood, in the State of Pennsylvania, have invented a new and useful Improvement in Machines for Finishing Articles of Glassware; and I do hereby declare the following to be a full, clear, and exact description thereof.

My invention relates to machines for finishing articles of glassware.

The object of my invention is to provide a machine in which the finishing-tools which revolve around the article are gradually brought into contact with the article, their pressure against the article being governed by centrifugal force.

To this end my invention comprises, generally stated, a shaft having pivotal arms mounted thereon, carrying the finishing-tools, and means for imparting a gradually increased speed to said shaft, whereby the centrifugal force will act to force the finishing-tools into contact with the article.

To enable others skilled in the art to make and use my invention, I will describe the same more fully, referring to the accompanying drawings, in which—

Figure 1 is a longitudinal section of my improved machine. Fig. 2 is a plan view of a portion of the machine. Fig. 3 is a different form of my invention, in which the finishing-tools work on the interior of the article. Fig. 4 is a section on the line 4-4, Fig. 3. Fig. 5 is another arrangement of the finishing-tools.

Like letters indicate like parts in each of the figures.

The letter *a* designates a portion of a suitable frame upon which the working parts of my invention are mounted. Within the bearings *b* in said frame is journaled the vertical rotary shaft *c*, said shaft being free to move vertically in said bearings. For the purpose of raising and lowering said shaft *c* a treadle *d* is provided, with its forward end engaging the lower end of said vertical shaft *c*. A pulley *e* is secured to the shaft *c*, said pulley to be driven by a suitable belt. At the upper end of the shaft *c* is the speed-regulating disk *f*, which has the central boss *f'*, with the bevelled face *f''*. Beginning from the base of said boss *f'* the upper face of the disk *f* has the

spiral guideway or groove *f''* formed therein, extending to the outer rim of said disk. The uprights *a'* of the frame *a* have the bearings *a''*, in which is secured the horizontal shaft *g*. The outer end of this shaft *g* carries the former *g'*, which may be of any suitable shape, that shown being of a shape to conform to the interior of the ordinary tumbler. This former *g'* is secured to the shaft *g* by means of the screw *g''*, so that said former may be readily removed and another of different form substituted therefor. Surrounding the shaft *g* and free to rotate thereon is the shaft *h*, said shaft being held against longitudinal movement by the collar *h'*. Secured to the forward end of the shaft *h* is the collar *i*, with the lugs *i'* formed thereon. To these lugs *i'* are pivoted the levers *k*. On the forward ends of the levers *k* are the finishing-tools *l*. These tools are in the form of rollers and are free to revolve on the spindle ends *k'* of said lever. Other forms of tools may, however, be employed. Links *m* connect the inner ends of the levers *k* to the sliding ring *m'* on the shaft *h*. A spring *n*, interposed between the ring *m'* and the bearing *a''*, acts to compress the inner ends of said levers *k*, and consequently throws the outer ends thereof apart. Weights *o* are adjustably secured to the levers *k*. Brackets *p*, extending up from the frame, have the guides *p'*, which support the longitudinally movable rod *q*. Secured to the rod *q* and depending therefrom is the fork *r'*, which engages the flange *r''* on the sliding sleeve *r*. The sleeve *r* has the key *r''*, which engages with the keyway *h''* in the shaft *h*. At the opposite end of the sleeve *r* is the enlarged flange *r''*, which has its periphery so formed as to engage conveniently with the groove *f''* in the disk *f*. A cord or like flexible connection *s* is secured to the end of the rod *q*, said cord passing over the pulley *s'* and having the weight *s''* secured thereto, the tendency of the weight being to bring the sleeve *r* in such position that the flange *r''* will engage with the bevelled face *f''* of the boss *f'*, or, if not engaging therewith, will be adjacent thereto.

In Fig. 3 I have illustrated another form of my invention in which the finishing-tools are arranged to act on the interior of the arti-

cle instead of on the exterior, as above set forth. As the modification only relates to the forward end of the machine, I have only illustrated that portion.

- 5 The letter *t* represents the stationary shaft, and *t'* the rotary shaft. Within the forward end of the shaft *t'* is the rod *t''*. A spring *t''* encircles the rod *t''*, being interposed between the cap *t⁴* on the outer end of the shaft *t'* and the head *t⁵* of said rod *t''*. In order to effect the rotation of the rod *t''* with the shaft *t'*, a pin *t⁶* in the rod *t''* engages with the slot *t⁷* in the shaft *t'*, whereby said rod has also a certain amount of longitudinal play. Pivoted 15 to the lugs *u* on the cap *t⁴* of the shaft are the levers *u'*, said levers having the spindles *u²* at the forward end thereof, on which the finishing-tools *u³* are mounted and adapted to rotate. Links *u⁴* at the end of the rod *t''* are 20 also connected to the levers *u'*, forming a toggle-joint. As in this instance the tools act on the interior of the article, it is necessary to support the article from its exterior. Accordingly the mold *v* is provided, which is 25 portable, its halves being hinged by the pin *v'*. This mold is opened and closed by the lever *v²*. The inner end of the lever *v²* is secured to the arm *v³*, said arm passing up through a guide in the frame and being connected 30 at its upper end to the links *y y'*. These links *y y'* are each connected to the mold-halves, respectively. It is apparent that by the movement of the lever *v²* the mold *v* is readily opened and closed.
- 35 In Fig. 5 I have illustrated a different arrangement of the finishing-tools. This applies to cases where the tools are applied to the exterior and interior of the article at the same time. In this view the letter *x* represents the rotary shaft. The tools *x'* are the ones which act on the exterior of the article, and they are pivoted to the head *x²* of said shaft *x*. The inner ends of said tools have the teeth *x³*. The teeth *x³* mesh with corresponding teeth *z³* on the inner ends of the tools *z'*, which act on the interior of the article. The inner tools *z'* are made slightly heavier than the outer tools, so that when the shaft rotates the centrifugal force will tend 45 to throw out the tools *z'* to a greater extent than the outer tools *x'*, and the teeth of the inner tools meshing with the teeth of the outer tools will act to draw in the outer tools. In this manner one set of tools works on the exterior 50 of the article while the other works on the interior. Instead of having the inner tools heavier than the outer ones I may employ the weighted arms shown in dotted lines, Fig. 5, attached to the outer tools. The centrifugal force will throw these arms out and the tools *x'* in, whereby the inner tools *z'* will be thrown out.

60 The operation of my invention when in the form shown in Fig. 1 is as follows: In starting, the sleeve *r* will be in the position shown in dotted lines, Fig. 1—that is, the enlarged

flange *r⁴* will be adjacent to the beveled boss *f'*. The article *S* to be finished, which in this case is a tumbler, is mounted on the snap *4* and having been properly heated is advanced 70 onto the former *g'*. The snap is supported in the upright *5*. The operator then lowers the treadle *d* and raises the shaft *c*. This brings the disk *f* into contact with the flange *r⁴*. The rotation of the disk *f* rotates the flange *r⁴* or 75 contact member in frictional contact therewith, and consequently the shaft *h*. As the flange *r⁴* is in engagement with the spiral groove *f³* of the disk *f* close to the center of the disk, it is apparent that the shaft *h* will 80 begin to rotate slowly; but as the spiral groove *f³* carries the flange *r⁴* toward the periphery of the disk the shaft *h* will rotate at a gradually-increasing speed until the periphery is reached, when the shaft will continue 85 to rotate at the same rate of speed as long as the disk is elevated. This rotation of the shaft *h* imparts a like rotation to the levers *l*, carrying the finishing-tools. The centrifugal force tends to throw the inner ends of said 90 levers apart and the outer ends toward each other. The result is that the tools *l* are forced into contact with the exterior of the article and revolve in contact therewith. As the shaft *h* rotates at a gradually-increasing speed the 95 centrifugal force likewise increases gradually, so that the tools are forced against the article with a gradually-increasing pressure. After the pressure has reached its maximum point or the flange *r⁴* is engaging with the 100 outermost ring of the groove *f³* the tools may be allowed to act on the article until the same has been properly finished. The operator allows the shaft *c* to descend, freeing the disk *f* from engagement with the flange *r⁴*. The 105 weight *s²* immediately draws the sleeve *r* along the shaft *g* until the flange *r⁴* is restored to its original position. The flange *r⁴* may be allowed, if desired, to remain in contact with the beveled boss *f'*, so that the shaft *h* will 110 continue to rotate at low speed. The article finished is then removed and another substituted, when the operation just described is repeated.

When the invention is embodied in the 115 form shown in Fig. 3, the operation is the same as above described, the only difference being that the tools act on the interior of the article. The article *S* to be finished is mounted on the snap *7* and is inserted in the 120 mold *v* and the mold closed around it. The gradually-increased centrifugal force throws the tools into contact with the interior of the article. When the rotation ceases, the tools resume their normal positions and permit of 125 the withdrawal of the article therefrom, when said article is of the form of that shown. In the instances described the tools are carried by centrifugal force into contact with the article; but it is apparent that the article 130 may be carried into contact with the tool.

I do not wish to limit myself to the con-

structions illustrated, as these may be departed from without affecting the scope of my invention.

What I claim as my invention, and desire to secure by Letters Patent, is—

1. In apparatus for finishing articles of glassware, the combination with the finishing-tools, of the rotary shaft on which said tools are mounted, and means whereby the shaft, when it starts, can be driven at a speed less than normal, and the rate of speed thereof automatically and gradually increased until it reaches the normal rate.

2. In apparatus for finishing articles of glassware, the combination with the rotary shaft, of the finishing-tools, mounted thereon to move radially under the influence of the centrifugal force, and means whereby the shaft, when it starts, can be driven at a speed less than normal, and the rate of speed thereof automatically and gradually increased until it reaches the normal rate.

3. In apparatus for finishing articles of glassware, the combination with a suitable frame, of a rotary shaft, mechanism for driving said shaft at a uniformly gradually-increasing speed, tools on said shaft and rotating therewith, a support for the article to be finished, the centrifugal force carrying said tools into contact with the article, substantially as set forth.

4. In apparatus for finishing articles of glassware, the combination with a suitable frame, of a rotary shaft, a vertically-movable shaft, mechanism for rotating said shaft and for raising and lowering same, a disk on said vertical shaft having a spiral guideway formed therein, a contact member on said first-mentioned shaft adapted to engage said spiral guideway, swinging levers on said first-mentioned shaft, tools on said levers, and a support for the article to be finished, the centrifugal force carrying said tools into contact with said article, substantially as set forth.

5. In apparatus for finishing articles of glassware, the combination with a suitable frame, of a rotary shaft, a vertically-movable shaft, mechanism for rotating said shaft and for raising and lowering same, a disk on said vertical shaft having a spiral guideway formed therein, a sliding contact member on said first-mentioned shaft adapted to engage said spiral guideway, swinging levers on said first-mentioned shaft, tools on said levers, and a support for the article to be finished, the cen-

trifugal force carrying said tools into contact with said article, substantially as set forth.

6. In apparatus for finishing articles of glassware, the combination with a suitable frame, of a rotary shaft, a vertically-movable shaft, mechanism for rotating said shaft and for raising and lowering same, a disk on said vertical shaft having a spiral guideway formed therein, a sliding contact member on said first-mentioned shaft adapted to engage said spiral guideway, mechanism for moving said contact member along said shaft toward the center of said disk, swinging levers on said first-mentioned shaft, tools on said levers, and a support for the article to be finished, the centrifugal force carrying said tools into contact with said article, substantially as set forth.

7. In apparatus for finishing articles of glassware, the combination with a suitable frame, of a rotary shaft, a vertically-movable shaft, mechanism for rotating said shaft and for raising and lowering same, a disk on said vertical shaft having a spiral guideway formed therein, a sliding contact member on said first-mentioned shaft adapted to engage said spiral guideway, a weight for moving said contact member along said shaft toward the center of said disk, swinging levers on said first-mentioned shaft, tools on said levers, and a support for the article to be finished, the centrifugal force carrying said tools into contact with said article, substantially as set forth.

8. In apparatus for finishing articles of glassware, the combination with a suitable frame, of a rotary shaft, a vertically-movable shaft, mechanism for rotating said shaft and for raising and lowering same, a disk on said vertical shaft having a spiral guideway formed therein, a sliding sleeve on said shaft, a contact member on said sleeve adapted to engage said spiral guideway, a sliding rod, connections between said rod and sleeve, a weight connected to one end of said rod, swinging levers on said first-mentioned shaft, tools on said levers, and a support for the article to be finished, the centrifugal force carrying said tool into contact with said article, substantially as set forth.

In testimony whereof I, the said AUGUSTUS H. HEISEY, have hereunto set my hand.

AUGUSTUS H. HEISEY.
